UNITED STATES PATENT OFFICE.

ALEXANDER VROBLE, OF DETROIT, MICHIGAN.

CURTAIN SUPPORT.

Application filed April 8, 1924. Serial No. 704,917.

To all whom it may concern:

Be it known that I, ALEXANDER VROBLE, a citizen of the United States, residing at Detroit, in the county of Wayne and State of Michigan, have invented a new and useful improvement in a Curtain Support, of which the following is a specification.

My invention relates to a new and useful improvement in a curtain support, and has for its object the provision of a curtain support which will be simple in structure, economical of manufacture, and highly efficient in use.

Another object of the invention is the provision of a curtain support adapted for raising and lowering while having a curtain mounted thereon and associated with a supporting bracket for retaining the curtain support in horizontal position, while supporting a curtain.

Another object of the invention is the provision of a curtain support of the class described, having means associated therewith for supporting a curtain and a drape, so as to be readily movable relatively to the supporting bracket.

Other objects will appear hereinafter.

The invention consists in the combinations and arrangements of parts hereinafter described and claimed.

The invention will be best understood from a reference to the accompanying drawings, which form a part of this specification, and in which,

Fig. 1 is a front elevational view showing the invention used as a curtain support in a slightly lowered position,

Fig. 2 is a top plan view of the invention,

Fig. 3 is a perspective view of the bracket used with the invention,

Fig. 4 is a top plan view of a modified form of the invention.

With the invention used as a curtain support, it becomes possible to raise and lower the curtain from the ground, the use of ladders, and the like, being eliminated. The curtain is supported on a curtain rod arranged for raising and lowering in connection with a shade 8 which is mounted on a roller 7, supported by suitable brackets to be described hereinafter. Thrust through a sleeve formed in the shade 8, which is provided with the usual operating cord 9, is a supporting bar 10, having threaded ends 11 and 11'. The curtain support comprises a rod 12, having an angularly turned portion

13, an angularly turned portion 14 and an angularly turned portion 15. The threaded end 11' is projected through an opening formed in the portion 15, suitable nuts 16 and 17 being mounted on the portion 11 and 11', at opposite sides of the portion 15. The rod 12 is formed tubular and adapted for the reception, in telescopic relation, of a rod 18, the portion entering the rod 12 being reduced and terminating in an enlarged portion 19, having angularly turned portions 20, 21 and 22. The threaded portion 11 is projected through the portion 22, suitable lock nuts 16' and 17' being associated therewith, as described for the opposite end of the support. The threaded portions projecting through the angularly turned portions 15 and 22 permit the pivotal movement of the curtain support relatively to the portions 11 and 11'. The rod, or stick, 10 is also permitted to rotate in the sleeve so that, when the invention is moved to the position shown in Fig. 1, the curtain support hangs vertical. As the shade is rolled upwardly to elevate the curtain to normal position, the curtain support is brought into position to cause the angularly turned portions at the opposite ends to lie in horizontal position. This results from the end of the bracket supporting the roller. This bracket comprises a main body portion 26, having an angularly turned foot 25, which is adapted to be secured to the casing 24 of the window by screws, nails, or the like. The main body 26 is provided with a suitable slot 27 for the reception of the end of the roller, one of the brackets being provided, if desired, with a centrally positioned opening for the reception of the round trunnion projecting from the roller, as will be readily understood. The bracket is provided, at the outer end of the main body portion, with an angularly turned vertically extending arm 28 and intermediate its end, the main body is provided with an angularly turned horizontally extended arm 29.

When the curtain is raised to normal position from the position shown in Fig. 1, the angularly turned portions 21 and 14 engage against the arms 29 to prevent a further rolling of the shade 8 on the roller 7. The angularly turned arm 28 serves to also support the portions 22 and 15, so that the curtain is held considerable distance outwardly from the frame, or sash 24 of the window with which used.

The curtain is held to the support by suitable clips 23 and 23' mounted on the angularly turned portions 14 and 21.

In Fig. 4, I have shown a modified form 5 of the invention whereby the curtain support is associated with a pivotal support for drapes and the like. In the modified form, a drape support rod 31 is provided, having connected with it a portion 32 10 through which the threaded ends 11 and 11' are adapted to be projected, as already described. The portion 32 has an angularly arranged portion provided with the portion 33 in parallel relation to the portion 31. 15 A curtain supporting rod 34 is adapted for association with the portion 33, in telescopic relation, and this supporting rod 34 is adapted for association with another section 35, the number of sections desired being determined by the width of the window 20 with which the device is to be used. Sections may be telescopically arranged on the portion 31 to give them any desired length, even extending them across the entire width 25 of the window, if desired.

While I have illustrated and described the preferred form of structure, I do not wish to limit myself to the precise form of structure shown, but desire to avail myself of such 30 variations and modifications as come within the scope of the appended claims.

Having thus described my invention, what I claim as new and desire to secure by Letters Patent is:

- 35 1. A curtain support comprising a supporting member adapted for association with a roller shade; means for attaching said supporting member to said roller shade in pivotal relation thereto; and angularly turned portions on said supporting member 40 adapted for lying in horizontal position when moved to normal position and adapted to lie in vertical position when out of normal position.
- 45 2. A curtain support of the class described comprising a supporting portion having angularly turned portions at opposite ends thereof; means for attaching said

angularly turned portions to a shade roller with which used; a bracket for supporting said shade roller and laterally turned portions on said bracket adapted for engaging said angularly turned portions of said supporting member, when said supporting member is in normal position for supporting said angularly turned portions in horizontal position.

3. A curtain support of the class described comprising a supporting member having angularly turned portions at opposite ends thereof; means projected through said angularly turned portions for attaching the same to a roller shade with which used; a roller for supporting said shade; a bracket for supporting said roller; and a plurality of laterally turned arms on said bracket for engaging said angularly turned portions and supporting the same upon the movement of said supporting member into normal position.

4. A curtain support comprising a supporting member having angularly turned portions at opposite ends; a rod connecting said angularly turned portions and adapted for attaching the same to a roller shade with which used; a roller for supporting said shade; a bracket for supporting said roller; and laterally outwardly projecting arms for engaging said angularly turned portions for supporting the same when in normal position.

5. A curtain support of the class described comprising a supporting member having angularly projecting portions at opposite sides thereof; means for mounting said supporting member on a roller shade with which used; a roller for supporting said shade; a bracket for supporting said roller; and means associated with said bracket for engaging said angularly turned portions for retaining the same in horizontal position, when moved to normal position.

In testimony whereof, I have signed the foregoing specification.

ALEXANDER VROBLE.
